UNITED STATES PATENT OFFICE.

FRANK KUHN, OF DETROIT, MICHIGAN.

THERMOSTATIC ELECTRIC SWITCH.

1,130,985.

Specification of Letters Patent.

Patented Mar. 9, 1915.

Application filed April 18, 1913. Serial No. 762,157.

To all whom it may concern:

Be it known that I, FRANK KUHN, a citizen of the United States of America, residing at Detroit, in the county of Wayne and

5 State of Michigan, have invented certain new and useful Improvements in Thermostatic Electric Switches, of which the following is a specification, reference being had therein to the accompanying drawings.

10 The invention relates to thermostatic electrical switches, and consists in the novel construction as hereinafter set forth.

In the drawings: Figure 1 is a perspective view of a switch; Fig. 2 is a longitudinal 15 section therethrough; and Fig. 3 is a cross section.

A is a section of metallic tubing, and B is a metallic bar formed of a material having a different coefficient of expansion and 20 of a slightly bowed form, as shown. The bar B is arranged inside of the tube A, and is secured to one of the sides thereof by screws or other fastening devices C at opposite ends. To facilitate the attachment 25 of the member B the tube A is cut away upon the opposite side at D so as to provide an opening for the insertion of a screw-driver or other engaging tool.

Upon the outer face of the tube and opposite the bar B is secured a contact member E, which is insulated from the tube by an interposed insulation F of mica or other suitable insulator material. The contact 30 member E is secured in this position by screws G, which pass through insulator bushings H in the member E into engagement with a threaded aperture in the member A. An insulator washer I interposed between the head of the screw G and the 35 member E completes the insulation.

40 J is a contact screw which is secured to the member E and passes through an aperture in the tube A into proximity or into contact with the member B.

45 In operation, one of the terminals of the electric circuit is attached to the tube A and the other to the contact member E. This will normally close the circuit by the passage 50 of current through the contact screw J, the free end of which is in contact with the bowed bar B. As soon, however, as a certain temperature is reached, the differential expansion of the bar B and tube A will cause the former to separate slightly from 55 the contact screw J, so that the circuit is

open. Upon the cooling of the parts, the screw and curved bar will again come into contact, which will close the circuit.

Where the bar B is formed of a metal having a comparatively low fusing point, 60 it is desirable to provide a contact thereon of different material, such as shown at K. This contact co-operates with the contact screw J in the manner above described.

What I claim as my invention is: 65

1. A thermostatic switch, comprising a metallic tube, a bowed member formed of metal having a different co-efficient of expansion than said tube and arranged within the same, means for securing said bowed 70 member to said tube, an insulation mounted upon one face of the tube, a metallic strip mounted upon said insulation, insulated securing means connecting said metallic strip and insulation to said tube, and a contact 75 member mounted upon said metallic strip, insulated from said tube and projecting into the latter into operative relation to the bowed member.

2. A thermostatic switch, comprising a 80 metallic tube, a bowed member formed of a metal having a different coefficient of expansion arranged within said tube and secured to one of the sides thereof at its opposite ends, a contact member mounted upon 85 and insulated from said tube on the side opposite said bowed member, means for securing said contact member to said tube and a contact screw engaging said outer contact member and passing through an aperture in 90 said tube into operative relation with said bowed member.

3. A thermostatic switch, comprising a metallic tube of rectangular cross section, a bowed bar formed of a metal having a different 95 coefficient of expansion arranged within said tube and secured at its opposite ends to one of the sides of said tube, a contact member adjacent to the outer face of said side, insulation interposed between said contact 100 member and said tube, insulated devices for securing said contact member to said tube, and a contact screw engaging said contact member and extending through an aperture in said tube into operative relation with said 105 bowed bar.

4. A thermostatic switch, comprising a metallic tube of rectangular cross section, a bowed bar formed of metal having a different 110 coefficient of expansion arranged within

said tube and secured at its opposite ends to one of the sides of the tube, the opposite side of said tube opposite the ends of said bowed bar being cut away, a contact member adjacent to the outer face of the side of the tube to which said bowed member is secured, said contact member being insulated therefrom, and a screw engaging said contact

member and extending within said tube into operative relation with said bowed bar.

In testimony whereof I affix my signature in presence of two witnesses.

FRANK KUHN.
